UNITED STATES PATENT OFFICE

169,260

COOKING TOP

Arleigh G. Hupp, New Albany, Ind.

Application January 2, 1952, Serial No. 17,896

Term of patent 14 years

(Cl. D81—25)

To all whom it may concern:

Be it known that I, Arleigh G. Hupp, a citizen of the United States, residing at New Albany, in the county of Floyd and State of Indiana, have invented a new, original, and ornamental Design for a Cooking Top, of which the following is a specification, reference being had to the accompanying drawing, forming part thereof.

In the drawing:

Figure 1 is a perspective view of a cooking top embodying my new design; and

Figure 2 is a top plan view thereof.

I claim:

The ornamental design for a cooking top, as shown.

ARLEIGH G. HUPP.
